UNITED STATES PATENT OFFICE.

GEORGE C. MURRAY, OF CHICAGO, ILLINOIS.

DRAW-BAR AND YOKE.

1,175,548.

Specification of Letters Patent. Patented Mar. 14, 1916.

Application filed January 20, 1912. Serial No. 672,408.

To all whom it may concern:

Be it known that I, GEORGE C. MURRAY, a citizen of the United States, residing at Chicago, in the county of Cook and State of Illinois, have invented certain new and useful Improvements in Draw-Bars and Yokes, of which the following is a specification.

The object of my invention is to provide an improved draft rigging yoke of the general type illustrated in my Patent No. 1,000,932, August 15, 1911.

The particular objects and nature of my invention will more clearly appear from the following description and claims, taken in connection with the accompanying drawings, in which—

Figure 1 is a plan view of a draft rigging embodying my invention. Fig. 2 is an elevation of the structure shown in Fig. 1. Fig. 3 is a transverse section on the line 3-3 of Fig. 1. Fig. 4 is an end view of the inner end of the yoke. Fig. 5 is a view of the inside of the upper yoke member. Fig. 6 is a view of the inside of the lower yoke member. Fig. 7 is a fragmentary view in section; showing the hinged ends of the yoke member. Fig. 8 is a fragmentary perspective view of the outer end of the lower yoke member. Fig. 9 is a plan view of another embodiment of my invention. Fig. 10 is an elevation view of the structure shown in Fig. 9.

The purpose of a draft rigging yoke of the general form described herein is set forth in my patent above referred to. In the particular embodiment of my invention illustrated the yoke comprises an upper member 1 and a lower member 2, provided at their inner ends with eyelets 3-4 through which a hinge pin or pintle 5 extends. At its outer end the upper yoke member 1 is provided with depending ears 6 between which the draw-bar 7 is received. The lower yoke member 2 is provided with depending ears 8 which lie inside of the depending ears 6 of the upper yoke member, and the ears 8 are provided at their lower edges with outward projections 9 turned up at 10 to form anchors for the lower edges of the ears 6, and thereby prevent the ears 6 from spreading.

It is one of the purposes of my present invention to make the construction compact, thus taking up less of the space between the draft sills, and this object is accomplished by having the ears upon the lower yoke

member project downwardly therefrom inside of the ears upon the upper yoke member. In this form of construction, it is necessary to provide between the draft sills 60 only for the thickness of the ears upon the upper yoke member, and owing to the considerable length of the ears 6 I provide the anchor seats 9-10 to prevent said ears from spreading, although this particular feature 65 of the construction may not in all cases be necessary or may be accomplished by other specific arrangement falling within the scope of my invention.

In order to secure the yoke to the draw-bar 7, which is of a form now in use, I provide a key 11 which passes through registering key openings in the ears 6 and in the draw-bar 7, and in order to hold the upper and lower yoke members together and in engagement with the draw-bar, as shown in Fig. 2, I provide a key 12 which passes through registering key openings in the ears 6 and 8. The upper and lower yoke members are provided, according to the usual 80 practice, with inturned outer ends 13 which engage the shoulders 14 upon the draw-bar. I have also shown lugs 15 upon the draw-bar between which lugs and the shoulders 14 the inturned ends of the yoke are received. The shoulders 15, however, are not essential in the structure shown in Figs. 1 and 2 but are desirable in the form of the device shown in Figs. 9 and 10. In the construction described draft stresses are transmitted from the draw-bar 7 to the yoke 90 through the key 11 and through the lugs 14.

The key 11 passes through elongated slots 16 in the draft sills and at its outer end receives cotter pins 17 passing through apertures 18'. The cotter pins 17 serve to hold the key 11 against displacement, and by placing the cotter pins upon the outer sides of the draft sills they are in a position which renders assemblage of the device and taking 100 it apart convenient.

In order to prevent displacement of the hinge pintle 5 I provide apertures 18 in the eyelet upon one of the yoke members, in this case the upper yoke member, and provide a 105 registering aperture 19 through the pintle 5. A cotter pin 20 is inserted through the apertures in the eyelet 4 and in the hinge pin and serves to hold the hinge pin in place. It will be noted that the lower yoke member 2 is cut away at 21 between the eyelet 3 for the purpose of affording clearance for

the lower end of the cotter pin 20. By placing the cotter pin in the position described, I am enabled to have the ends of the hinge pin 5 flush with the sides of the yoke, thereby avoiding the possibility of the projecting ends of the hinge pin striking against the draft rigging lugs 22 or other parts of the mechanism.

In Figs. 9 and 10 I have shown a form of my improved yoke in which no key is employed passing through the yoke and draw-bar. In this construction the draw-bar 30 is provided with the lugs 31 and shoulders 32, and the lugs 33 and 34 upon the upper and lower yoke members engage the recess between the lugs 31 and shoulders 32 on the draw-bar. A key 35 passes through the depending ears upon the upper and lower yoke members as in the construction above described and serves to hold the upper and lower yoke members together with their lugs 33 and 34 in engagement with the recess in the draw-bar. In this construction upon buffing movements the yoke is carried back with the draw-bar by the lugs 31 and pulling strains are transmitted to the yoke through the engagement of the shoulder 32 upon the draw-bar with the lugs 33, 34 upon the yoke.

I claim:

1. In a device of the class described, a draw-bar, a yoke comprising an upper and a lower member connected together at their

inner ends, said upper yoke member having ears depending at its outer end at the sides of said draw-bar, said lower yoke member 35 having depending ears lying inside of the ears upon the upper yoke member, the ears upon the lower yoke member being turned outwardly and upwardly at their lower ends to engage the outer sides of the ears upon 40 the upper yoke members.

2. In a device of the class described, a draw-bar having shoulders adjacent its inner end and lugs adjacent said shoulders, a yoke comprising upper and lower members 45 connected together at their inner ends and having inturned outer ends engaging the draw-bar between the said lugs and shoulders thereon, said upper yoke member having depending ears between which the draw-bar is 50 received, said lower yoke member having depending ears lying inside of the ears upon the upper yoke member, a key engaging registering apertures in said ears, and a second key engaging registering apertures in said 55 draw-bar and in the ears depending from said upper yoke member.

In testimony whereof, I have subscribed my name.

GEORGE C. MURRAY.
